HEAT EXCHANGER

Meinhard H. Kotzebue, Tulsa, Okla.

Application September 18, 1936, Serial No. 101,512

12 Claims. (Cl. 257—255)

This invention relates to heat exchangers and the primary object of the invention is to provide a practical, efficient heat exchanger which is simple in construction and may be manufactured at a relatively low cost.

Another object of the present invention is to provide in a heat exchanger a novel type of support plates for the tubes thereof, which support plates are constructed of a plurality of sections and are held in place by removable means, whereby the support plates may be removed while the heat exchanger is in operative position, to permit the giving of temperature shocks to the tubes for the purpose of removing scale from the outside of the tubes, which scale accumulates thereon due to the evaporation of cooling water on the tubes.

A further object of the present invention is to provide in a heat exchange headers which are small in size and still will not result in a material pressure drop of the liquid entering and leaving the tubes.

Further objects of the present invention are to provide a heat exchanger in which the supporting structure or frame is made up of fabricated sheet metal and angular iron to provide an inexpensive structure, and one wherein the headers or fluid boxes are connected directly to the tube heads by removable bolts which lie wholly within the outer contour of the heat exchanger.

With these and other objects in view, as may appear from the accompanying specification, the invention consists of various features of construction and combination of parts, which will be first described in connection with the accompanying drawings, showing a heat exchanger of the preferred form embodying the invention, and the features forming the invention will be specifically pointed out in the claims.

In the drawings:

Figure 1 is a top plan of the improved heat exchanger having parts broken away.

Figure 2 is a cross section through the heat exchanger taken on approximately the line 2—2 of Figure 1.

Figure 3 is a fragmentary horizontal section through the heat exchanger taken on the line 3—3 of Figure 4.

Figure 4 is a fragmentary vertical section through the heat exchanger taken on the line 4—4 of Figure 1.

Figure 5 is an end view partly in section of the inlet and outlet header of the heat exchanger.

Figure 6 is a horizontal section through the

inlet and outlet head and taken on the line 6—6 of Figure 5.

Figure 7 is a section through the inlet and outlet head or fluid box and taken on the line 7—7 of Figure 1.

Figure 8 is a detail section taken on the line 8—8 of Figure 1.

Figure 9 is a slightly enlarged detail section illustrating the manner of supporting the tubes intermediate their ends.

Figure 10 is a detail cross section taken on the line 10—10 of Figure 5.

Figure 11 is a fragmentary perspective view of one of the support plates.

Figure 12 is a fragmentary perspective view of the supporting frame or structure of the heat exchanger showing fragments of the headers or fluid boxes thereon.

Referring more particularly to the drawings, the improved heat exchanger is what is commercially known as an atmospheric heat exchanger wherein a fluid, such as hot fractionated petroleum is passed through the tubes of the exchanger for the purpose of cooling the fluid, and the tubes are exposed so that cooling water may be showered over the tubes, the entire heat exchanger immersed in a tank of cooling water, or the circulation of air about the tubes may be utilized as a cooling medium, and the present heat exchanger embodies a supporting frame 1 which has tube sheets 2 and 3 removably connected at each end thereof, which tube sheets have the tubes 4 connected thereto in the usual manner. The fluid to be cooled enters the inlet and outlet head 5 through a suitable inlet 6, circulates or passes through a predetermined portion of the tubes into the return head 7, is returned to certain other of the tubes by the arcuate partition 8 formed in the head 5 and finally returns through the final pass into the head 5 and thence outwardly through the outlet 9. While in the drawings, a four-pass heat exchanger is illustrated, that is, a heat exchanger in which the fluid to be cooled passes four times through the length of the exchanger, it is to be understood that a heat exchanger embodying any desired number of passes may be provided without departing from the spirit of the present invention.

For the purpose of facilitating the manufacture and assembly of the heat exchanger and for the purpose of materially reducing its cost, a novel type of supporting frame is provided. This supporting frame 1 comprises side members 10 which are preferably formed of sheet metal cut

away to form openings 11 through which the cooling medium passes for circulation about the tubes 4. The side members 10 have their edges bent to form substantially right angular flanges 12 which extend throughout the entire length of the heat exchanger and are detachably connected by means of bolts indicated at 13 to angular irons 14 which are welded or otherwise suitably attached to the tube heads 2 and 3. Slots 15 are provided in the angular irons 14 to compensate for expansion and contraction of the tubes under heat variances. As clearly shown in Figures 8 and 10 of the drawings, the headers or fluid boxes 5 and 7 are detachably connected directly to the tube sheets 2 and 3 respectively by means of bolts 16 which extend through the tube sheets and are disposed wholly within the outer contour of the tube heads. The disposing of the bolts 16 wholly within the outer contour of the heat exchanger 20 is permitted by reason of the forming of the bolt receiving bosses 17 within the respective headers or fluid boxes.

The arcuate partition 8 forms a curved path for the liquid flowing from one pass or set of tubes into the next or subsequent pass or set of tubes and results in the provision of headers which are small in size and prevents any material pressure drop in the liquid flowing through the heat exchanger. The arcuate or substantially 30 semi-cylindrical partition 8 not only provides a curved path for the fluid flowing from the second to the third pass of the exchanger, but it also provides convexly curved surfaces leading the fluid to and from the tubes of the first and final 35 passes of the heat exchanger.

The tubes 4 are supported intermediate their ends by a novel type of support plate structure and these support plates which are generically indicated by the numerals 30 are each formed 40 of a plurality of independent sections 31. The sections 31 extend throughout the length of the support plates and transversely of the heat exchanger and they have their meeting edges substantially in the plane of the longitudinal axes 45 of the tiers of tubes as clearly shown in Figures 4 and 11 of the drawings. Consequently each section 31 has a series of cut-out portions 32 therein which receive substantially one-half of the tubes 4, and provide joints in the support plates whereby 50 the individual sections of the support plates may be removed for cleaning the tubes of scale in the manner hereinafter more fully described. The sections 31 of each of the support plates 30 rest against braces 33, the ends of which are 55 angled as shown at 34 and rest against and may be welded to the flanges 12 of the side members 10 of the supporting frame 1. Removable pins 35 are inserted through the flanges 12 and engage the sides of the sections 31 oppositely to the 60 sides of the sections which engage against the braces 33. The pins 35 securely hold the support plate sections in position during the normal operation of the heat exchanger.

In the drawings the support plate sections 31 65 are illustrated as being made of wood or other material of greater pliability than the material of the tubes so as to prevent distortion of the tubes under heat variances, and while it is desirable to make the support plate sections of wood or analogous material, it is to be understood that 70 they may be made of any suitable material or metal without departing from the spirit of the present invention.

When it is desired to remove scale from the 75 outside of the tubes, the removable pins 35 are

removed, and the various sections 31 of the support plates are removed or turned upon their sides on the tubes so as to prevent their supporting action of the tubes. Steam is then put into the tubes which materially raises the temperature of the tubes, and causes expansion thereof, resulting in the elongation or buckling of the tubes. The scale which has accumulated on the tubes not having any tensile strength will crack under this treatment. The steam is then cut off and cold water is sprayed over the tubes. The spraying of the cold water over the tubes causes them to contract or shrink in both length and diameter, and such contracting action will cause the scale to fall from the tubes. However, such scale as 1 does not fall from the tubes will have water collected under it where it has been loosened from the tubes, and a re-application of high pressure steam suddenly applied to the tubes will cause such water to be converted into steam so rapidly 2 that it will readily blow the scale from the tubes. Due to the rapid expansion, the tubes will writhe, further assisting in the removal of the scale.

It will be noted by particular reference to Figures 2 and 4 of the drawings, that the tubes in 2 the various tiers of the heat exchanger are disposed staggeredly with respect to the tubes in the tiers next thereto so as to provide proper distribution of the cooling medium over all of the tubes.

It will be understood that the invention is not to be limited to the specific construction or arrangement of parts shown but that they may be widely modified within the invention defined by the claims.

What is claimed is:

1. In a heat exchanger, a supporting frame, tube sheets detachably connected to the ends of said frame, support plates for said tubes intermediate said tube sheets, said support plates being made up of a plurality of independent sections, braces for said frame carried thereby and forming abutments against which one side of the sections of the support plate engage, and removable pins carried by said supporting frame and 45 engaging said support plate sections on the sides opposite to those engaging said braces.

2. In a heat exchanger, a supporting frame consisting entirely of a pair of oppositely disposed side members, tube sheets detachably connected to the ends of said side members, tubes carried by said tube sheets, braces intermediate the ends of said side members, a support plate for said tubes, said support plate abutting said braces, and removable means carried by said side members and engaging said support plate to hold it 55 against said braces.

3. In a heat exchanger, a supporting frame consisting entirely of a pair of oppositely disposed side members, tube sheets detachably connected to the ends of said side members, tubes carried by said tube sheets, braces intermediate the ends of said side members, a support plate for said tubes, said support plate abutting said braces, and removable pins carried by said side 60 members and removable from the exterior of the supporting frame, said pins engaging said support plate for holding the support plate against said braces.

4. In a heat exchanger, a supporting frame 70 consisting entirely of a pair of oppositely disposed side members, tube sheets detachably connected to the ends of said side members, tubes carried by said tube sheets, braces intermediate the ends of said side members, a support plate 75

for said tubes, said support plate abutting said braces, removable pins carried by said side members and removable from the exterior of the supporting frame, said pins engaging said support plate for holding the support plate against said braces, said supporting plate being formed of a plurality of sections, and means detachably connecting said tube sheets to said side members to permit limited relative movement of the support sheets and side members to compensate for expansion and contraction of the tubes.

5. In a heat exchanger, a supporting frame consisting entirely of a pair of oppositely disposed side members, tube sheets detachably connected to the ends of said side members, tubes carried by said tube sheets, braces intermediate the ends of said side members, a support plate for said tubes, said support plate abutting said braces, removable means carried by said side members and engaging said support plate to hold it against said braces, and fluid boxes detachably connected to said tube sheets independently of the connection of the tube sheets with said side members.

6. In a heat exchanger, a supporting frame consisting entirely of a pair of oppositely disposed side members, tube sheets detachably connected to the ends of said side members, tubes carried by said tube sheets, braces intermediate the ends of said side members, a support plate for said tubes, said support plate abutting said braces, removable means carried by said side members and engaging said support plate to hold it against said braces, fluid boxes detachably connected to said tube sheets independently of the connection of the tube sheets with said side members, an arcuate partition in one of said fluid boxes and cooperating with the walls thereof to provide a curved return passage and inlet and outlet chambers in the fluid box, and fluid inlet and outlet connections on said fluid box provided with the partition.

7. In a heat exchanger, a supporting frame composed wholly of two oppositely disposed side members and being provided with openings therein to permit cross-circulation through the exchanger, tube sheets detachably connected to the ends of said side members, and fluid boxes detachably connected to said tube sheets independently of the connection of the tube sheets with the supporting frame.

8. In a heat exchanger, a supporting frame, a plurality of tubes, a support plate for said tubes formed of a plurality of sections of wood, the meeting edges of said sections being substantially 55 in the planes of the longitudinal axes of the tubes, abutment means carried by said frame, the sides of said support plate sections at their ends engaging said abutments, and a removable pin carried by said frame and extending across and 60 engaging the sides of said sections opposite the sides engaging said abutments at each end to

hold the sections in contact with said abutments whereby the sections may be removed by removal of the two pins.

9. In a heat exchanger, a supporting frame, a plurality of tubes, a support plate for said tubes 5 formed of a plurality of sections, abutment members carried by said frame, one side of each of said support plate sections at their ends engaging said abutments, and a removable pin carried by said frame and extending across and engaging 10 the other sides of said sections at each end to hold the sections in contact with said abutments.

10. In a heat exchanger, a supporting frame, tube sheets at the ends of said frame, fluid boxes 15 removably attached to said tube sheets, tubes carried by said tube sheets, slip slot and bolt connections between said supporting frame and tube sheets to compensate for expansion and contraction of said tubes, a support plate for said tubes said support plate being built up of a plurality of sections, abutment members carried by said frame, one of the sides of each of said support plate sections at their ends engaging said abutments, and removable pins carried by said frame and extending across the other sides of 25 said sections at each end to hold the sections in removable contact with said abutment members.

11. In a heat exchanger, a supporting frame composed entirely of two oppositely disposed side members having their edges angled and being 30 provided with openings therein to permit cross-circulation through the exchanger, tube sheets detachably connected to the ends of said members, tubes carried by said tube sheets, a support plate for said tubes, abutment members carried 35 by the angled edges of said side members and engaged by the sides of said support plate sections at their ends, and removable pins carried by said side members and engaging against the sides of said sections opposite to the sides engaging said 40 abutment members for removably holding the sections against the abutment members.

12. In a heat exchanger, a supporting frame composed entirely of two oppositely disposed side members having their edges angled and being 45 provided with openings therein to permit cross-circulation through the exchanger, tube sheets, tubes carried by said tube sheets, a support plate for said tubes, abutment members carried by the angled edges of said side members and engaged 50 by the sides of said support plate sections at their ends, and removable pins carried by said side members and engaging against the sides of said sections opposite to the sides engaging said abutment members for removably holding the 55 sections against the abutment members, angle brackets carried by said tube sheets, and slot and bolt connections between said angle brackets and tube sheets to compensate for expansion and contraction of the tubes.

60

MEINHARD H. KOTZEBUE.
